UNITED STATES PATENT OFFICE.

OSCAR T. NELSON, OF CLEVELAND, OHIO, ASSIGNOR OF FIFTY PER CENT. TO C. A. BARNHOLTH, OF AKRON, OHIO.

INTERNAL-COMBUSTION ENGINE.

1,336,371.

Specification of Letters Patent.

Patented Apr. 6, 1920.

Application filed January 19, 1917. Serial No. 143,227.

To all whom it may concern:

Be it known that I, OSCAR T. NELSON, a citizen of the United States, residing at Cleveland, in the county of Cuyahoga and State of Ohio, have invented a certain new and useful Improvement in Internal-Combustion Engines, of which the following is a full, clear, and exact description.

This invention relates to an internal combustion engine. The object of the invention is to provide a rotary valve in the engine head for the purpose of controlling the admission of fuel and the exhaust of burned fuel from the cylinder, and in addition to the rotary valve to provide a subsidiary valve which will act to seal the passages which coöperate with the rotary valve when the charge of fuel is being compressed in the cylinder.

20 A further object of the invention is to provide an engine with a rotary valve in which there is provision for running the engine in opposite directions, and providing a driving mechanism for the valve which will position itself correctly to operate the valve when the engine is driven in either direction.

Further objects will become apparent as the invention is further described.

30 Generally speaking, the invention may be said to comprise the elements and combinations thereof set forth in the accompanying claims.

Reference should be had to the accompanying drawings, forming a part of this specification, in which Figure 1 is a front elevation of an engine having my invention applied thereto; Fig. 2 is a top plan view showing the mechanism outside of the engine, by which the valves are operated; Fig. 3 is a sectional elevation showing a single cylinder of an engine and its coöperating structure; Fig. 4 is a section upon the line 4-4 of Fig. 3; Fig. 5 is a top plan view of a single cylinder of an engine; and Fig. 6 is a top plan view of the rotating valve, the ports with which the valve coöperates being shown in dotted lines.

While the invention is applicable to an engine having any number of cylinders, a four-cylinder engine being shown in Fig. 1, inasmuch as the mechanism associated with each cylinder is the same, it will suffice to describe the mechanism for a single cylinder.

der, and in addition to describe a mechanism by which all the valves are operated.

Referring to Fig. 3, the cylinder of the engine is indicated at 1, the outer jacket at 2, it being understood that water or other cooling fluid may be circulated within the jacket 1. Within the cylinder is the piston 3, which by a piston rod 4 is connected with the crank shaft.

Above the cylinder there is provided a head 5 which is in two parts, the upper or outer part being indicated at 5^a. Within a suitable recess formed in the head 5^a there is mounted a valve 6. This valve at its central portion is secured to a post or pin 7 which extends through the portion 5^a to the exterior thereof, and upon the outside there is a disk 8 which is secured to the pin 7. As before stated, the pin is secured to the valve 6 and extends below the same as indicated at 7^a, into a suitable recess in the head 5, thus forming a bearing.

In the head 5 there are three openings indicated at 10, 11, and 12. The openings 10 and 12 are inlet openings, that is to say, they are openings through which fuel is admitted to the cylinder, while the opening 11 is an exhaust opening.

When the engine is running in a given direction the openings 10 and 11 will coöperate, and when the engine is running in the opposite direction the openings 11 and 12 will coöperate, that is to say, when the engine is running in a given direction, either the opening 10 or 12, but not both, will coöperate with the outlet 11.

A manifold 13 extends by the various cylinders and coöperates with an inlet portion 14 carried by the cylinder which we are describing, and there is also a passageway 15 formed in the head 5^a which communicates with the portion 14 so that the manifold may distribute fuel either to the opening 10 or 12 as may be required by the direction in which the crank shaft is turned.

The exhaust opening 11 which is a complementary opening upon the head 5^a, coöperates with an exhaust pipe 16.

The inner end of each of the openings 10 and 12 is provided with a slanting portion 10^a and 12^a which form valve seats and receive valve heads 17 and 18. The two valves being similarly constructed and operated, the valve 17 only will be described.

Coöperating with the valve head is a valve stem 19 which at its lower end has a plunger head 20 secured thereto. The plunger head extends within a recessed portion 21 formed in the engine head, and the upper part of this recess receives a plug 22 which fits tightly within the recess, and the plug is provided with an opening from which extends the stem 19. Packing is provided upon the stem as indicated at 23.

The lower portion of the opening 21 communicates by means of a passageway 24 with the space above the cylinder. Through the engine head there is an opening 25. This opening extends to and communicates with the opening 21 previously described. Coöperating with this opening is a chambered member 26 in which there is a small plunger 27, the plunger having a stem 28 which extends through a head 29 of the member 26. The head 29 is provided with a vent hole 30. The valve 6 is provided with an inwardly extending flange 6^a which extends into a suitable groove provided in the head 5, this groove serving to in a measure guide the movement of the valve 6 and also to provide a packing. The packing is an oil packing and for the purpose a groove 6^b is provided in the downturned portion 6^a. This groove is filled with oil by pumping the same through the opening 30 which is ordinarily closed. This oil packing not only serves to lubricate the valve 6, but forms a seal so that the gases may not escape around the flange 6^a of the valve.

In the valve head 5 surrounding the various openings therein are packing rings which are indicated at 31. These may also assist in the lubrication if desired. The openings in the valve head 5 are somewhat peculiar in shape as will be noted from Fig. 6. The outer and inner portions of the openings are circular in form, while the sides are straight, the general effect being somewhat that of a keystone.

The opening in the valve 6 which coöperates with the various openings in the head 5, is indicated at 6^c, and this opening is of the same general shape as the openings 10, 11, etc. The openings are given their peculiar shape so as to maintain the exhaust open as wide as possible through the range of time during which the portion 6^a of the valve 6 is coöperating with the exhaust, and similarly to quickly open up as large an opening as possible when the opening 6^c is coöperating with the inlet opening in the head. It will be seen that the opening 6^c and the openings with which it coöperates are of such shape and size that the opening 6^c begins to coöperate with the opening 10 just as soon as it is leaving the opening 11.

It will be understood that as the valve 6 rotates, immediately it leaves the exhaust opening 11, it passes into registry with the

opening 10, and during the time it is passing into and out of registry with the valve 10, the piston 3 is descending and so drawing in a charge of fuel. At the time that the opening 6^c leaves the valve 10, the piston 3 begins to compress the charge which has been drawn in, and continues to compress the charge that is being drawn in until the piston 3 has reached its upper or outermost position, at which time the charge is exploded, driving the piston 3 in a manner well understood. During these operations the valve 6 is continuously moving, and at the time the piston 3 begins to ascend on its scavenging stroke the openings 6^c and 11 80 are beginning to register, and during the time that the opening 6^c starts to register and passes beyond its registering position the piston is on its scavenging stroke.

During the operation just described there 85 of course was a period when the opening 6^c was in registry with the opening 12, but at such time there was gas under compression in the space immediately above the cylinder 1, and this operating upon the lower face 90 of the valve 18, held the valve to its seat so that the fact that the opening 6^c was registering with the opening 12 was of no consequence in the operation of the engine.

During the time that gas, either fuel or 95 exploded gas under compression was in the space above the cylinder 1, the compressed gas not only held the valve 18 closed as just described, but also the valve 17. These valves 17 and 18 thus prevent the compressed gas from escaping around the valve 6 as might be the case if that valve were alone employed.

At the time there is compressed gas in the space above the cylinder, there is pressure 105 not only against the end face of the valve 17 but also against the lower face of the plunger 20 so that the pressures upon both the valve head 17 and the plunger 20 are co-operating to hold the valve 17 in closed position.

The space above the plunger 20 which communicates with the casing 26 is preferably filled with air which is confined; when the plunger 20 rises, this air will be compressed in the passageways and in the casing 26, and will be held in compressed condition while the pressure acting against the valve 17 and the lower face of the plunger 20 is sufficient to overcome the pressure of the 120 air within the chamber 26 and the passage 25.

When the piston is starting its intake stroke and the opening 6^c begins its registry with the opening 10, the descent of the piston 3 creates a negative pressure or suction upon the lower surface of the plunger 20 and the pressure of the air confined above the plunger 20 also acts to push the plunger 20 downward and so move the valve 17 away 130

from its seat and permits the passage of gas past the valve 17.

Each disk 8 is provided with a pin 33 which is secured in a corresponding opening 5 in a rod 34 so that all the valves of the various cylinders are operated together. The ends of the rod 34 are connected to pins 35 and 36 which are mounted upon rings 37 that lie within cup-shaped members 38. The 10 cup-shaped members are provided with two projecting members 39 and 40 and between these members there is an ear 41.

When the cup-shaped member 38 is turning in a counter-clockwise direction the ear 15 41 will coöperate with the projection 39, and when the cup-shaped member 38 is turning in the opposite direction the ear 41 will co-operate with the projection 40.

The cup-shaped member 38 is secured to a 20 shaft 42 which coöperates with bearings 43. At the lower end of the shaft is a gear 44 which meshes with a gear 45 upon the crank-shaft. Thus the shaft 42 is driven from the crank-shaft.

25 The arrangement for driving at the opposite end of the crank-shaft is similar to that which has just been described and as will be clearly seen from the drawings.

If the engine be driven in the opposite direction, that is to say, in a direction opposite to that which we may assume it has been going when the ear 41 is in contact with the projection 39, the first turning of the shaft 42 and the cup-shaped member 38 will not 30 turn the valve 6 until the gear 41 is moved so as to contact with the projection 40. However, during this movement of the crank shaft the pistons will have moved, and this movement of the pistons during the time 35 40 that the valve has remained stationary will be sufficient so that the opening 6^a in the valve 6 will coöperate with the openings 12 and 11 in proper sequence and times with respect to the movement of the pistons.

45 It will thus be seen that the change necessary in the positioning of the valve with respect to the movement of the pistons, is accomplished automatically by the varying movement of the crank shaft in the opposite 50 direction and requires no attention or setting upon the part of the operator.

Having thus described my invention, I claim:

1. In an internal combustion engine, the 55 combination with a cylinder and a piston therein of a head coöperating with the said cylinder, said head having an intake port and an exhaust port, said intake port being out of line with the cylinder, a rotating 60 valve in said head said valve being provided with a port, means for turning the valve to coöperate with said ports in the head in proper sequence, a valve mounted at one side of the cylinder, said valve coöperating 65 with the inlet port in the head between the

cylinder and the rotating disk, said second valve being closed by gas under pressure with the cylinder.

2. In an internal combustion engine, the combination with a cylinder and piston 70 therein of a head coöperating with the cylinder, said head being provided with an inlet port and an exhaust port, a rotatable valve coöperating with the said head, said valve being provided with a port a cover member 75 coöperating with the head of the valve, and inclosing the rotatable valve between the said head and the cover, said cover having ports which register with the ports in the head and means for turning the said valve. 80

3. In an internal combustion engine, the combination with a cylinder and piston 85 therein of a head coöperating with the cylinder, said head being provided with an inlet port and an exhaust port, a rotatable valve coöperating with the said head, said valve being provided with a port a cover member 90 coöperating with the head of the valve, and inclosing the rotatable valve between the said head and the cover, said cover having ports which register with the ports in the head and means for turning the said valve, a second valve which is mounted at one side of the cylinder, said second valve coöperating 95 with the inlet valve in the said head, said second valve being closed by gas under pressure within the cylinder.

4. In an internal combustion engine, the combination with a cylinder and piston 100 therein of a head coöperating with said cylinder, said head being provided with an annular groove adjacent its edge, said head being provided with an inlet port and an exhaust port, a rotatable valve having a 105 flange at its outer edge which occupies the groove in the head, said rotatable valve having a port, a cover member, coöperating with the head and inclosing the rotatable valve and means for turning the valve.

5. In an internal combustion engine, the 110 combination with the cylinder and the piston therein of a head coöperating with said cylinder, the head being provided with an intake and an exhaust port, said head being provided with grooves which encircle 115 the said intake port and exhaust port, packing rings in said groove, said head being also provided with an annular groove adjacent its edge, a rotatable valve having a flange at its edge which occupies the last mentioned 120 groove in the head, a cover member coöperating with the head and inclosing the rotatable valve and means for turning the said valve.

6. In an internal combustion engine, the 125 combination with a cylinder and piston therein, a head for said cylinder, there being an inlet opening and an exhaust opening in the said head, of a rotary disk valve within the head, a single opening in the 130

4
said valve, means for turning the valve to successively coöperate with the openings in the head, and a second valve between the cylinder and the first mentioned valve, said second valve being closed by gas under pressure within the cylinder.

7. In an internal combustion engine, the combination of a cylinder having a piston therein, a head for the cylinder, of a disk 10 valve within said head, said head being provided with an inlet opening and an exit opening, the said valve being provided with a single opening which coöperates with the said openings in the head in proper sequence, 15 and a check valve coöperating with the inner end of the inlet opening whereby gases under compression within the cylinder will cause the said check valve to close.

8. In an internal combustion engine, the 20 combination with a cylinder having a piston therein and a head for the cylinder, of a rotating valve within the head of the cylinder, said head being provided with an inlet opening and an exhaust opening and said valve 25 being provided with a single opening which coöperates in proper sequence with the said openings in the head, the inner end of the inlet opening in the head having a valve seat, a valve adapted to coöperate with said 30 seat, said valve having a stem, means for guiding the said stem, and means compressed when the valve moves to its seat under pressure, which means serves to open the valve when the said pressure is relieved.

35 9. In an internal combustion engine, the combination of a cylinder having a piston therein and a valve head having a rotating valve therein, the head being provided with an inlet opening and an exit opening and 40 the valve being provided with a single opening which coöperates with the said openings in proper sequence, the inner end of the inlet opening being provided with a valve seat, a valve coöperating with said seat, a valve 45 stem carried by the valve, a plunger at the opposite end of the valve stem, an opening in which the plunger lies, the said plunger coöperating with the side walls thereof to form a tight connection, a channel coöperating 50 with the lower end of the opening in which the plunger is located and communicating with the space above the cylinder, and means for holding air under compression associated with the opening in which 55 the plunger is located above said plunger.

10. In an internal combustion engine, the combination of a cylinder having a piston

therein and a head for the cylinder, said head being provided with two inlet ports and a single exhaust port, a rotary valve 60 within the head having a single opening which coöperates with one of the inlet openings and the exhaust opening when the valve is turning in one direction and coöperates with the other of the said inlet openings and 65 the exhaust opening when the valve is turning in the opposite direction, and means for turning the said valve, said means being driven by the engine, the connection being such that when the engine is reversed the 70 valve assumes a new position with respect to the operation of the cylinder.

11. In an internal combustion engine, the combination of a cylinder having a piston therein and a head for the cylinder, two inlet ports and an exhaust port in the cylinder head, a rotary valve within the cylinder head said valve being provided with a single opening which when the valve is turning in one direction coöperates with one of the inlet openings and the exhaust opening, and when the valve is turning in the opposite direction coöperates with the other inlet opening and the exhaust opening, and means 80 for turning the valve, said means being connected with the engine to be driven thereby, said means including a slip connection so that when the engine is driven in the opposite direction the valve assumes a new position with respect to the operation of the 90 cylinder.

12. In an internal combustion engine, the combination with a cylinder having a piston therein and a cylinder head, of a rotatable valve within the cylinder head, said head being provided with two inlet openings and an exhaust opening, said valve being provided with an opening which when turning in one direction coöperates with one of the inlet openings and the exhaust, and when turning 100 in the opposite direction coöperates with the other of the inlet openings and the exhaust, valvular means coöperating with the inner portions of the said inlet openings, said valves being moved to closed position when 105 gas under pressure is within the cylinder thereby to seal the said openings against the escape of gas, and means for operating the first mentioned valve to coöperate with either of the inlet ports and the exhaust 110 port.

In testimony whereof, I hereunto affix my signature.

OSCAR T. NELSON.
